UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922. Serial No. 543,658.

This invention pertains to improvements in lubricating apparatus. It is among the objects of the invention to provide simple and efficient mechanisms for quick connection and disconnection of a source of lubricant under pressure with lubricant-receiving parts.

In the drawings, which show a preferred form of one embodiment of my invention:—
10 Figure 1 is a side elevation of a lubricating device;

Fig. 2 is a central longitudinal section through the nozzle or discharge end of the device shown in Fig. 1, the lubricant-receiving nipple shown in elevation immediately after entrance thereof within the nozzle of the device;

Fig. 3 is a view similar to Fig. 2, showing the relation of the parts pursuant to the initial relative turning movement between nozzle and nipple;

Fig. 4 is a view pursuant to the coupling and valve opening operations;

Fig. 5 is an end elevation taken from the left of Fig. 1;

Fig. 6 is a section on the line 6—6 of Fig. 4;

Fig. 7 is a side elevation of the nozzle, the sleeve removed to show the interior parts thereof;

Fig. 8 includes a side and two end elevations of one of the interior nozzle parts;

Fig. 9 is a section on the line 9—9 of Fig. 3; and

Fig. 10 is a section on the line 10—10 of Fig. 4.

Referring to the drawings and to the preferred form of my invention selected for illustrative purposes, I have shown a lubricant supply device typified by the barrel 11 having a rear head 12 into which is threaded the usual stem 13 carrying at its outer end the handle 14 and having at its inner end the usual lubricant-expelling piston (not shown).

The discharge nozzle or terminal portion includes coupling means and valve means for cooperation with a lubricant-receiving nipple 15 having an enlarged portion 16 presenting underlying shoulders and having at one end the usual lubricant-receiving opening with check valve 17. The coupling means illustrated includes a coupling sleeve

18, herein shown as retractile relative to its cooperating parts, notably a sealing part 19 carrying the sealing washer 20.

The coupling sleeve 18 is connected to the front head 21 of the "gun" by pins 22 carried by the latter and entering slots 23 in the latter. The sealing part 19 is held against rotation relative to the nipple 15 by suitable means typified by the projections 25, 25 (Fig. 4).

During the initial coupling operation, the coupling sleeve 18 will turn with the head 21 relative to the nipple and sealing part 19 until the projections on the nipple 15 are underlain by the flange portions 30 of the coupling, as shown in Fig. 5. During this initial coupling operation, turning between 70 the sleeve 18 and sealing part 19 may take place, the pins 31, 31 moving in the slots 32, 32 from one end thereof to the opposite end (as shown in Fig. 6) where the sleeve 18 can no longer turn, and the extensions 75 33 permit retractile movement of the sleeve 18 to be actuated by the inclined portion of the slots 23 acting on pins 22 to retract the sleeve and provide the tight joint.

During this coupling and sealing operation, the valve has been moving toward the opening position shown in Fig. 4, where the slot 39 extending across all but the periphery of the face of the valve disc 40 registers with the ports 41 in the sealing part to admit 85 passage of lubricant therethrough to the nipple 15.

As the pin 31, cooperating with the pin 22, opposes initiation of sealing until after the interlock between the nipple and sleeve 90 18 is completed, so during uncoupling the pin 31 engaging the steep side of the extension 33 of the slot 32 prevents any relative turning between the nipple 15 and sleeve 18, to release the interlock therebetween, until after the valve is closed and the pin 22 returned to its position shown in Fig. 7, thus completely releasing the seal.

The sealing part 19 is not integral with the head 21, but may move longitudinally 100 relative thereto and therefore the movement of the pin 22 in the slot 23 may continue even after the sealing part 19 is firmly pressed against the head of the nipple, the head 21 during this period moving forward 105 while the sealing part 19 and valve disc 40

- remain stationary axially considered. The pin 50 which holds the valve disc against rotation relative to the head 21 has a slotted connection to permit this axial movement.
- 5 The parts are preferably so constructed that a small amount of this axial movement will precede communication of the valve ports, thus insuring a tight seal. To prevent over difficult operation when the lubricant in the 10 barrel is under high pressure prior to opening of the valve, the effective valve area is greatly reduced by the reduced rear end 51 of the valve structure fitting a reducing plug 52 in the front head with appropriate cut 15 washer 53. The valve disc may be further pressed toward its seat by a valve spring 54 which is desirable when the pressure in the lubricant barrel is slight.
- Even where the parts are so proportioned 20 that no axial movement of the valve disc 40 takes place the reduction at 52 is desirable because it prevents excess pressure between the valve parts when the lubricant in the barrel is under great pressure. Where no 25 such axial movement is provided, it is desirable that a recess be made back of the sealing gasket 20 so that tightness of the seal may be insured by pressure of the lubricant pursuant to opening of the valve.
- 30 While I have shown and described a preferred form of one embodiment of my invention, it will be understood that changes involving omission, substitution, alteration and reversal of parts, and even changes in the 35 mode of operation, may be made without departing from the scope of my invention, which is best defined in the following claims.

Claims:

1. Lubricating apparatus including a 40 source of lubricant under pressure having a coupling sleeve rotatable relative to a nipple to provide an interlock with projecting means provided on the nipple, a cooperating sealing part and means for initiating re-

traction of said sleeve relative to the sealing part following completion of the interlock. 45

2. Lubricating apparatus including a source of lubricant under pressure having a coupling sleeve rotatable relative to a nipple to provide an interlock with projecting 50 means provided on the nipple, a cooperating sealing part and means for initiating retraction of said sleeve relative to the sealing part subsequent to completion of the interlock and while said sleeve is held against 55 further rotative movement.

3. Lubricating apparatus including a source of lubricant under pressure having a coupling sleeve rotatable relative to a nipple to provide an interlock with projecting 60 means provided on the nipple, a cooperating sealing part and means for initiating retraction of said sleeve relative to the sealing part pursuant to completion of the interlock and while said sleeve is held against 65 further rotative movement, and cooperating valve means openable upon completion of retractile movement of said sleeve.

4. A lubricating apparatus comprising a source of lubricant under pressure including a retractile coupling sleeve, sealing means therein and a rotary valve controlling flow of lubricant to a lubricant receiving nipple, said valve openable only upon completion of the coupling and sealing operations. 70

5. A lubricant-expelling device comprising means providing a source of lubricant under pressure, a retractile coupling sleeve at the discharge end of said device for coupling engagement with the lubricant-receiving nipple, and a rotary valve operable by rotation of said sleeve with respect to the nipple for controlling flow of lubricant to the nipple. 80

In testimony whereof, I have signed my name to this specification.

HOWARD J. MURPHY.
